UNITED STATES PATENT OFFICE.

WILLIAM TAPPE, OF WEST UNION, WEST VIRGINIA.

BOX-LID HOLDER OR HANGER.

1,233,142.

Specification of Letters Patent. Patented July 10, 1917.

Application filed November 17, 1916. Serial No. 131,931.

To all whom it may concern:

Be it known that I, WILLIAM TAPPE, a citizen of the United States, residing at West Union, in the county of Doddridge and 5 State of West Virginia, have invented new and useful Improvements in Box-Lid Holders or Hangers, of which the following is a specification.

This invention relates to box lid holders or 10 hangers adapted for general application, but particularly intended for use on jewelry boxes, and the primary object of the invention is to provide a device of this class which may be readily applied to the interior of a 15 box body and a hinged lid therefor without requiring the formation of recesses or cutting away any part of the box members and thereby permitting the use of the improved device upon a box and lid or cover constructed from very thin material. A further object of the invention is to provide a 20 holder or hanger for a box and hinged lid wherein the parts are comparatively simple in structure and may be assembled in operative 25 relation and having a positive operation without liability of jamming and which will also act as a reinforce relatively to the hinges connecting a lid or cover to a box body by holding the said lid or cover 30 steady or against lateral movement, thereby reducing the wearing strain on the hinges and their fastenings.

The invention consists in the construction and arrangement of the several parts which 35 will be more fully hereinafter described and claimed.

In the drawing:

Figure 1 is a transverse vertical section through a box body showing the lid or cover 40 thereof open and in elevation and illustrating the improved holders or hangers applied thereto.

Fig. 2 is a section of the box and lid or cover in a plane at a right angle to the section shown by Fig. 1 with the lid or cover closed.

Fig. 3 is a section of a box and lid or cover in the same plane as that shown by Fig. 2 with the lid or cover open.

50 Fig. 4 is a detail perspective view of one of the holders or hangers and showing the fulcrum clip which is attached to the box body by separate detail.

Fig. 5 is a detail perspective view of the 55 slide clip forming part of the holder or hanger.

Fig. 6 is a transverse vertical section of a portion of a box showing a modification in the application and construction of a part of the holder or hanger.

Fig. 7 is a detail perspective view of a modified form of fulcrum clip shown by Fig. 6.

The numeral 5 designates a box body to which a lid or cover 6 is connected by 60 hinges 7. This box body and its lid or cover may be of any suitable dimensions and adapted for different uses.

The improved holder or hanger comprises a flat slide bar 8 having deflected 70 or bent ends 9 with openings therein to receive fastenings, thereby causing the main body of the slide bar to stand outwardly from the said ends. On the slide bar 8 a slide clip 10 also constructed of 75 sheet or flat metal is mounted to move and the members thereof are held in proper spaced relation by a space member 11 secured therein, the ends 12 of the slide clip being formed as eyes to serve as a fulcrum 80 means for one end of a stay brace 13 which may be of any length and contour and held connected to the said eyes by a fulcrum pin or rivet 14. The holder or hanger also includes a fulcrum clip 15 consisting of a 85 longitudinal bar or plate 16 with fastening openings 17 in opposite ends and a hook or fulcrum member 18 bent upwardly at an angle from one edge parallel to the bar or plate 16 and terminating at its free end in 90 an eye 19 to form a fulcrum connection for the end of the stay brace 13 opposite that held between the ears 12, the end of the stay brace being inserted between the eye 19 and the bar or plate 16 and connected to the said 95 eye by a fulcrum pin, as at 20, see Figs. 1, 2 and 3. The opposite ends of the stay brace 13 are formed as eyes 21 and are readily attachable respectively to the ears 12 and the eye 19.

In applying the improved stay brace the slide bar 8 is placed against the one inner side of the lid or cover 6 and secured in parallel relation to said side; and in applying the slide bar 8 the slide 10 and stay 105 braces are simultaneously positioned and the stay brace ready for final attachment to the eye 19 of the fulcrum clip 15 which is secured against the inner side of the body 5 of the box. The holders or hangers are 110 preferably applied to opposite sides of the box body and lid or cover, as shown by Fig.

1, and against the inner surface of the latter parts of the box, thereby dispensing with the necessity of recessing, cutting or otherwise mutilating the box body or the lid or cover and adapting the improved holder or hanger to be used with box bodies and lids or covers constructed of very thin material. The operation of the holders or stay braces will be readily understood. As the lid or 10 cover 6 is closed the slides 10 freely move longitudinally on the slide bars 8, and said slides and slide bars being formed of flat metal lateral movement or vibration of the slides 10 and the stay braces is prevented. 15 The space members 11 are so positioned within the slides 10 as to leave ample space between the opposite side members of the slides to permit the latter to freely move over the slide bars 8 without binding, but at 20 the same time the slides 10 are not so loose as to allow lateral play relatively to the slide bars. In opening the lid or cover the slides 10 shift on the flat slide bars 8 toward the hinged end of the lid or cover, as 25 shown by Fig. 3, the stay braces 13 then standing across the rear of the box body at an angle. When the lid or cover 6 is closed the stay braces 13 fold closely adjacent to the sides of the box body and lid or cover, 30 as shown by Fig. 2, and do not in the least interfere with the contents of the box.

All the parts of the improved holder or hanger are made from sheet metal and may be readily assembled and applied to the box body and lid or cover as above explained. 35 It will be understood that the proportions of the several parts of the holder or hanger may be varied at will and also that sheet metal of varying thickness may be employed 40 in constructing the several parts in accordance with the general dimensions thereof.

Fig. 6 shows the slide bar 8 applied to the inner side of the box body 5 and engaged by the slide clip 10. To the lid 6 a fulcrum 45 clip 15^a is secured as shown, said fulcrum clip being illustrated by Fig. 7 and provided with a pair of apertured ears 15^b standing at right angles to the body thereof at the center. This fulcrum clip 15^a is secured against the box lid 6 as shown by Fig. 6, and the stay brace 13 is attached at

its ends to the slide clip 10 and fulcrum clip 15^a. This form of the holder or hanger is particularly adapted for use with a box and lid of light construction or made of thin 55 material and will be found very effective in operation.

What is claimed as new is:

In a box lid holder or hanger, the combination with a body member and a lid or 60 cover member hinged thereto and movable downwardly upon and upwardly from the said body member, flat slide bars secured to the inner portions of the opposing sides of one of said members in parallel relation 65 to said sides and standing inwardly from the latter for a greater portion of their length, fulcrum clips secured to the inner opposing sides of the other member and provided with ear means bent at an angle 70 and having transversely aligned openings at intermediate points with relation to the said clips, stay braces at opposite sides of the members having one end of each pivotally connected to the ear means of the clips, and 75 slide clips shaped to conform to and freely movable on the flat slide bars and having the opposite ends of the stay braces pivoted thereto, the slide clips being provided with outwardly projecting terminal ears between 80 which the ends of the stay braces are movably held and also having a space member between the ears and the adjacent edges of the slide bars and between the side portions of the said slide clips to prevent too 85 loose movement of the slide clips on the slide bars, the projecting ears of the slide clips disposing the ends of the stay braces attached thereto in positions for clearance of the several parts of the holders or 90 hangers and to insure an easy pivotal action, the space members of the slide clips also acting to resist strain on and bending of the ears of the said clips.

In testimony whereof I have hereunto set 95 my hand in presence of two subscribing witnesses.

WILLIAM TAPPE.
